CLAIM

The ornamental design for a wire terminal, as shown and described.

DESCRIPTION

FIG. 1 is a perspective view of a wire terminal showing my new design;

FIG. 2 is a front elevational view thereof;

FIG. 3 is a rear elevation view thereof;

FIG. 4 is a top plan view thereof;

FIG. 5 is a bottom plan view thereof;

FIG. 6 is a right said elevational view thereof; and,

FIG. 7 is a left side elevational view thereof.

The broken lines in FIGS. 1-4, 6 and 7 illustrate environmental subject matter only and form no part of the claimed design.

1 Claim, 7 Drawing Sheets(56)
